LOCK

Elmer B. Stone and Louis M. Dyson, New Britain, Conn., assignors to The American Hardware Corporation, New Britain, Conn., a corporation of Connecticut

Application February 6, 1934, Serial No. 709,958

7 Claims. (Cl. 70—93)

Our invention relates more particularly to that type of locks commonly known as pin tumbler locks, and an object of our invention, among others, is to provide a lock of this type which 5 may be differently operated by different keys.

One form of a lock embodying our invention and in the construction and use of which the objects herein set out, as well as others, may be attained, is illustrated in the accompanying 10 drawing, in which—

Figure 1 is a side view of our improved lock.
Figure 2 is an end view of the same.

Figure 3 is a view looking at the opposite end of the lock from that shown in Figure 2.
Figure 4 is a view similar to Figure 3 but showing the plug in one position possible by the operation of one form of key.

Figure 5 is a similar view but showing the plug placed in another position by another form of 20 key.

Figure 6 is a detail view on enlarged scale in central longitudinal section showing the position of the pin tumblers as placed by one key.

Figure 7 is a view in section with parts broken 25 away and illustrating the position of the pin tumblers as placed by another form of key.

Figure 8 is a view in section on a plane denoted by the dotted line 8—8 of Figure 7.

Figure 9 is a view in cross-section on a plane 30 denoted by the dotted line 9—9 of Figure 7.

Figure 10 is an isometric view partially in section illustrating the case and the locking sleeve 35 therein.

Figure 11 is an isometric view partially in section illustrating the key plug and a portion of the locking sleeve.

It is desirable to provide locks used in connection with various structures with means for operation by different keys, one key being limited 40 in the results produced by its operation over the results produced by the use of another key, or one key effecting one purpose and another key effecting another purpose. A lock embodying these features is illustrated and described herein, the drawing representing a lock case 12 for tumblers and a cylinder 13 for a key plug 14. The plug 14 is provided with a key slot 15 extending longitudinally through it, this slot being of any desired shape and form to permit the 45 entrance of keys of different shapes as common in lock structures of this type. Holes 16 are formed in a line extending lengthwise of the plug on one side, these holes being for the reception of the key engaging sections 17 of pin tumblers, said sections having rounded ends for engage-

ment with notches 18 in a key 19 of one form usable with my improved lock.

A hub 20 is secured to the inner end of the plug projecting beyond the case 12 and said hub may have means for connection to mechanism for operating releasing mechanism as for drawers or other receptacles in a manner common to structures of this class and which will be readily understood by those skilled in the art without further detail description.

A slot 21 is formed in the plug near the front end thereof and within the cylinder 13, said slot being for the purpose of receiving a stop 22 projecting from a locking sleeve 23, and as shown in Fig. 7 of the drawing.

This locking sleeve is fitted to the plug 14 inside of a shoulder formed by a head 24 on the plug, the sleeve being preferably of a length equal to the length of the cylinder 13 and terminating at the shoulder formed by the reduced end of the 20 plug upon which the hub 20 is secured. This sleeve has holes 25 to receive intermediate sections 26 of pin tumblers which rest against the key engaging sections 17, and as shown in Fig. 7. This sleeve is cut away at its inner end as at 27 25 forming shoulders at opposite ends of said cut that act as stops 28 to receive a stop pin 29 projecting inwardly from the inner wall of the cylinder 13.

The case 12 is formed with holes 30 to receive 30 the inner sections 21 of pin tumblers and springs 32 are seated against the sections 31 and against a closing plate 33 preferably of dove-tailed shape fitting a slot in the wall of the case 12 and as shown in Figs. 6 and 9 of the drawing. The 35 springs press the tumbler sections toward the key, the rounded ends of the sections 17 resting against shoulders 34 formed at the entrance of the holes 16 into the key slot.

In the operation of the lock a key 19 being 40 inserted therein the notches are so formed that the tumblers will be positioned with the inner ends of the key engaging sections all in line at the line of separation 35 between the plug and the sleeve 23, and as shown in Fig. 6 of the drawing. This will enable the key to turn the plug 14 in a contra-clockwise direction and to the position shown in Fig. 4, in which position the stop pin 22 will prevent further movement. This 45 operation will cause the plug to operate any desired mechanism to release any particular part which it is intended shall be unlocked, it being understood that in this operation the sleeve 23 is held against rotation by the intermediate sections of 50 55

the tumblers projecting into the openings in the lock case.

When a key as 36 is inserted in the slot the notches are so formed that the tumblers will be positioned with the meeting ends between the intermediate sections 26 and the inner sections 31 on a line between the sleeve and the inner wall of the case 12, and the plug may now be turned by the key in either direction until rotation is prevented by contact of the pin 29 with the stops 28. If the key be rotated contra-clockwise as in the case of the key 19 the same unlocking mechanism will be operated and if the key be turned in a clockwise direction other mechanism for unlocking or releasing other parts of the structure will be operated.

It will now be seen that by the use of a key, as 19, the lock may be operated to attain only one result, as the opening of a certain drawer or compartment of a receptacle, whereas by the use of a key, as 36, the same result, as with the operation of the key 19, may be attained, and other results, as access to other compartments, may be effected, and it may also be noted that the stop 28 may be so arranged, if desired, that the key 36 may turn in one direction only, and opposite to that permitted by use of the key 19, in which case each key would be limited in use to attain a result different from that obtained by the use of the other key.

In accordance with the provisions of the patent statutes we have described the principles of operation of our invention, together with the device which we now consider to represent the best embodiment thereof; but we desire to have it understood that within the scope of the appended claims the device shown is only illustrative and that the invention may be carried out by other means and applied to uses other than those above set out.

We claim—

1. A lock including a cylinder with a key plug member therein, means for controlling rotation of said plug member, a sleeve member within which said plug is rotatably mounted, a stop projecting radially from one of said members into a slot in the other of said members to permit rotation of the plug in one direction only from its normally locked position by the use of a key, and means to permit rotation of said plug in an opposite direction from its normally locked position by the use of another key.

2. A lock including a cylinder with a key plug rotatably mounted therein, means for controlling rotation of said plug, a slot extending circumferentially within the outer surface of said plug, a stop projecting radially from said sleeve into said slot to permit rotation of the plug in one direction only from its normally locked position by the use of a key, shoulders formed on said sleeve on opposite sides of a line extending diametrically across the sleeve, and a pin projecting from said cylinder into the path of movement of said shoulders.

3. A lock including a cylinder with a key plug therein, means for controlling rotation of said plug, a sleeve within which said plug is rotatably mounted, a stop separate from said controlling means and projecting radially from said sleeve into a slot in said plug to permit rotation of the plug in one direction only from its normally locked position by the use of a key, and means to permit rotation of said plug in an opposite direction from its normally locked position by the use of another key.

4. A lock including a cylinder with a key plug therein, means for controlling rotation of said plug in said cylinder, a sleeve in said cylinder and within which sleeve said plug is rotatably mounted, a stop projecting from said sleeve substantially at the opposite side thereof from said pin tumblers into a slot in said plug to permit rotation of the plug in one direction only from its normally locked position by the use of a key, and means for permitting rotation of said plug in opposite directions from its normally locked position by the use of another key.

5. A lock including a cylinder with a key plug therein, pin tumblers in said plug and cylinder to control rotation of the plug, a sleeve within which said plug is rotatably mounted, a stop projecting from said sleeve substantially at the opposite side thereof from said pin tumblers into a slot in said plug to prevent its rotation in one direction from its usually locked position by the use of a key, said tumblers being arranged to prevent rotation of the sleeve in such rotation of the plug, and means to permit rotation of the sleeve and plug in an opposite direction by the use of another key.

6. A lock including a cylinder with a key plug therein, a sleeve in said cylinder and within which said plug is rotatably mounted, pin tumblers having sections appurtenant to said cylinder, said sleeve and to said plug, a stop projecting from the sleeve into a slot in the plug to prevent its rotation in one direction from its normally locked position by the use of a key, means to position the tumblers to permit rotation of the plug in the sleeve, said tumblers being arranged to permit rotation of the sleeve in the cylinder by the use of another key.

7. A lock including a cylinder with a key plug therein, a sleeve in said cylinder and within which said plug is rotatably mounted, a stop projecting from said sleeve into a slot in said plug to prevent its rotation in one direction from its normally locked position, pin tumblers having sections appurtenant to said cylinder, sleeve and plug, said tumblers being arranged to be positioned by a key to permit rotation of the plug in the sleeve, and said tumblers also being arranged to be positioned by another key to lock the plug to the sleeve and to permit rotation of the sleeve in the cylinder, and means for limiting the rotation of said sleeve in said cylinder.
